UNITED STATES PATENT OFFICE

JOHN WICKS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE

AUTOMATIC TELEPHONE SYSTEM

Original application filed August 26, 1926, Serial No. 131,575. Divided and this application filed July 15, 1929. Serial No. 378,225.

This invention relates to telephone systems in general, but is more particularly concerned with automatic telephone systems in which toll connections are established through the medium of operator-controlled automatic switches. In such a system, automatic switches such as a toll first selector, toll transmission selector, one or more intermediate selectors, and a connector are successively operated under the control of a dial at the toll operator's positions. This invention further pertains especially to that kind of automatic telephone system in which the motor magnets of the automatic switches are directly operated by current impulses produced by the line relay of the transmission selector, the line relay of the transmission selector being operated by impulses produced by the dial of the calling operator.

20 The main object of this invention is the provision of new and improved automatic switches for use in a direct pulsing automatic telephone system. The main feature resides in the circuit arrangement whereby the current impulses for operating the magnets of the switches produced by the line relay of the first selector repeater are transmitted to the magnets of the switches over the two sides of the extended trunk line in series.

30 Other objects are accomplished and various features are contained in the invention which will be fully described in the body of this specification with the aid of the accompanying drawings.

35 This application is a division of my prior application Serial No. 131,575, filed August 26, 1926. Those features of the invention which relate generally to toll service are claimed herein, while the features relating to local service are claimed in the prior application.

Referring now to the accompanying drawings, Figs. 1-3 show by means of the usual schematic circuit diagrams a sufficient amount of the apparatus in a telephone system embodying the principles of this invention to enable the invention to be clearly described and understood.

The right-hand half of Fig. 1 shows the incoming toll selector TS. This toll selec-

tor terminates one of the toll trunks incoming from the office in which the main toll board is located. As many incoming toll trunks, terminating in similar incoming toll selectors, are provided as are necessary to carry the traffic to the office in question. In the banks of the incoming toll selectors, access is had to groups of toll transmission selectors.

55 The toll selector switch TS is of the ordinary Strowger vertical and rotary type and is operated according to the well-known two-wire system of control. Special off-normal springs are provided, however, to adapt it for use in the system being described.

55 The left-hand half of Fig. 1 shows the toll operator's cord CC by means of which toll connections are established over trunks extending to the various offices in the system, each trunk terminating at the toll board and a jack such as jack J. This cord is of standard type and forms no particular part of the invention itself. The circuit thereof will be described only in so far as is necessary to fully describe other apparatus controlled by means within the cord.

70 Fig. 2 shows the toll transmission selector TTS, which is one of a certain group of toll transmission selectors accessible in the banks of the incoming toll selectors. The banks of the toll transmission selectors are directly 75 multiplied with the banks of the local third selectors, and the toll transmission selectors and local third selectors are thereby given common access to the connectors.

75 Mechanically, the toll transmission selector TTS is also of the Strowger vertical and rotary type. The circuit arrangements, however, have been modified to meet the requirements of the invention and will likewise be described in detail hereinafter.

90 Fig. 3 shows the rotary connector RC, which is like the local connector C, shown in the above-referred-to application, except that it performs an automatic rotary hunting movement after completing its rotary directive movement. In its banks, access is had to groups of lines extending to private branch exchanges with the number of the first line assigned as the call number of the entire group. The rotary connector RC is one of a 95 100

group of rotary connectors accessible in the banks of a certain group of local third selectors multiplied with the banks of a certain group of toll transmission selectors. The first and last trunk of a group extending to the private branch exchange X, accessible to connector RC, are shown. Each trunk terminates in an individual line switch such as LS^s at the main exchange, and in a jack such as 10 jack J^s at the branch exchange. The line switch LS^s is of the well known rotary type having no normal or home position. A description of the operation of connector RC in so far as the novel features relating to 15 this invention are concerned will also be given.

To establish toll connections from the main toll board to a local P. A. X. subscriber, a new type of toll transmission selector, designed 20 especially to meet the requirements of this invention, has been provided. To describe the operation of this new type of toll transmission selector and to describe the operation of the new connector herein provided when utilized 25 in a toll connection, it will be assumed that a toll connection is desired with a subscriber at the P. A. X. "X" (Fig. 3). In this telephone system it is assumed that the main toll board is located at one exchange, 30 from which toll trunks extend to the other exchanges in the system.

It may now be assumed that the toll operator at the main toll board position answers the incoming toll call by means of the cord 35 circuit CC, Fig. 1, and, having learned the name or number of the called subscriber or P. A. X. inserts the calling plug P' of the cord CC into the jack of an idle toll trunk extending to the exchange serving the called subscriber. It may further be assumed that 40 the trunk selected is the one comprising conductors 501 and 502, terminating at the exchange under consideration in the selector TS. As previously stated, the selector TS is 45 of the well-known Strowger vertical and rotary type, the operation of which is well understood by those skilled in the art, and therefore a detailed description of its operation is thought unnecessary. After the toll operator 50 inserts the plug P' into the jack J she dials the directory number of the called subscriber. Responsive to the dialing of the first digit of 55 the called number, the selector S operates to position its wipers opposite the level of bank contacts, corresponding to the digit dialed, and then automatically rotates to position its 60 wipers 551—553 on a set of bank contacts terminating an idle trunk. It may be assumed that the idle trunk selected is the one comprising 65 conductors 554—556 accessible at bank contacts 554'—556'. It may be mentioned that the first digit of the called number as concerns the toll operator is the second digit in the directory number of the desired 70 station, since the operator in completing the

call manually selects the office to which the call is to be extended. When the trunk line comprising conductors 554—556 terminating in the toll transmission selector TTS is seized, ground potential is placed on the test 70 contact 555' to make the trunk busy, and a circuit is closed for the line relay 605 of the toll transmission selector TTS, which circuit may be traced from ground by way of armature 622 and the resting contact, conductor 556, 75 bank contact 556', wiper 553, working contact and armature 522, trunk conductor 502, ring of jack J, ring of plug P', contacts 503, contacts 505, lower right-hand winding of repeating coil R^s, winding of polarized relay 80 502, upper right-hand winding of repeating coil R^s, contacts 506, contacts 504, tip of plug P', and tip of jack J, conductor 501, armature 521 and the working contact, wiper 551, bank contact 554', conductor 554, normally closed springs controlled by armature 623, normally closed springs controlled by armature 628, through the upper winding of line relay 605 to battery. Line relay 605 operates and opens the short circuit around 90 resistance 619 and the upper winding of holding relay 608 at armature 632, and closes a circuit for release relay 606 at armature 631. Relay 606 operates and performs the following circuit changes: Ground potential is 95 placed on release conductor 555 to make the trunk engaged and to provide a holding circuit for selectors TS at armature 633, this taking place before the release relay in the selector TS has had time to fall back. A 100 point in the circuit of release magnet 614 is opened at armature 634. The circuit of the series relay 609 is prepared at armature 635, relay 609 being maintained deenergized at this time by reason of ground potential on its 105 upper terminal by way of the working contact and armature 631. At armature 636 a circuit is closed which may be traced from ground on the release conductor 555 supplied thereto by way of armature 633 and the working contact, normally closed springs controlled by armature 648, armature 646 and the resting contact, armature 636 and the working contact, resistance 619, through the upper winding of relay 608, armature 624 and the resting contact, springs controlled by armature 652, through the winding of vertical magnet 612 to battery. Due to the resistance of the upper winding of relay 608 and resistance 619, the current flow of this circuit is 110 insufficient to cause the operation of magnet 612. Relay 608 operates, however, and performs the following circuit changes: At armature 641 and the working contact, a circuit is closed for the supervisory relay 690 and lamp L^s in series, at the same time preparing the circuit for the lower winding of relay 608. At armatures 642 and 640 a new circuit is 115 closed for the upper winding of relay 608 which may be traced from ground by way of 120

125

130

the normally closed springs controlled by armature 647, armature 640 and the working contact, armature 636 and the working contact, resistance 619, upper winding of relay 608, working contact and armature 642, normally closed springs controlled by armature 652, through the winding of vertical magnet 612 to battery.

Responsive to the next digit dialed by the toll operator, line relay 605 deenergizes and 10 reenergizes a corresponding number of times. As a result, resistance 619 and the upper winding of relay 608 are short circuited, at armature 632 and the resting contact, a like 15 number of times which causes corresponding impulses of increased current flow in the circuit of the vertical magnet 612. Responsive thereto, vertical magnet 612 operates to position the wipers 661—664 opposite the level 20 of bank contacts corresponding to the digit dialed. Furthermore, each time that relay 605 deenergizes, ground potential is disconnected from the upper terminal of the series relay 609 and battery through the resistance 615 25 is substituted therefor by way of armature 631 and the resting contact. Relay 609, therefore, energizes over the circuit from ground through its own winding, working contact and armature 635 to battery by way of armature 30 631 and the resting contact and resistance 615, and also to battery through the winding of relay 606. Each time that relay 605 reenergizes during impulses, relay 609 is short circuited, and by reason of its being 35 short circuited, assumes slow-acting characteristics and, therefore, does not deenergize during the transmission of a series of impulses. Relay 609, in operating, closes an initial energizing circuit for stepping relay 40 610 at armature 644 which circuit may be traced from ground on release conductor 555, working contact and armature 644, resting contact and armature 650, off-normal springs 654 which are closed upon the first vertical 45 step of the switch wipers, through the winding of stepping relay 610 to battery. Relay 610 operates and prepares a circuit for the rotary magnet 613 at armature 645. In operating, relay 609 also closes the circuit for 50 the lower locking winding of relay 608 at armature 643. The closure of this holding circuit positively assures the continuous operation of relay 608 during the transmission of impulses, that is, during the time its upper winding is short circuited. Relay 610 55 also closes a temporary locking circuit for itself at armature 646 which may be traced from ground on release conductor 555, normally closed springs controlled by armature 648, armature 646 and the working contact, interrupting springs 653, off-normal springs 654, through the winding of relay 610 to battery.

At the end of this series of impulses, line 60 relay 605 is no longer deenergized and re-

mains energized continuously. Relay 609 is again continuously short circuited at armature 631 and the working contact and deenergizes. In releasing its armature 644, permitting the contacts controlled thereby to close, a circuit is closed for the rotary magnet 613 which may be traced from ground on release conductor 555, springs controlled by armature 644, working contact and armature 645, through the winding of rotary magnet 613 to battery. Armature 643 in releasing again closes the circuit for the supervisory relay 690. Rotary magnet 613 operates over the above-traced circuit and rotates the switch wipers 661—664 into engagement with the first set of bank contacts in the selected level and also opens the holding circuit for the stepping relay 610 at the interrupting contacts 653. Stepping relay 610 deenergizes and opens its own locking circuit at armature 646, 75 and opens the circuit of the rotary magnet 613 at armature 645. Magnet 613 releases and again closes interrupting springs 653. If the trunk line terminating in this first set of bank contacts is busy, ground potential will be present on the test contact encountered by test wiper 662. A circuit is then again closed for stepping relay 610 traceable from ground on the test contact, test wiper 662, armature 648 and the resting contact, interrupting springs 653, off-normal springs 654, through the winding of relay 610 to battery. Relay 610 again operates, closing the circuit of the rotary magnet 613 which again operates and steps the switch wipers 80 into engagement with another set of bank contacts. In this manner stepping relay 610 and magnet 613 operate alternatively, until the switch wipers are rotated into engagement with a set of bank contacts terminating an idle trunk. When an idle trunk line is found, which may be the trunk line comprising conductors 854—857 terminating in bank contacts 854'—857', no ground potential 85 will be present on the bank contact 855'. Consequently, no circuit will again be closed through the stepping relay 610. Therefore, 90 the wipers will be arrested in engagement with this set of bank contacts. Furthermore, the ground potential will be removed from the lower terminal of the switching relay 611, thus permitting this relay to energize over a circuit traceable from ground on release conductor 555, through the winding of relay 611, 95 interrupting contacts 653, off-normal springs 654, through the winding of the stepping relay 610 to battery. Due to the high resistance of the switching relay 611 the current flow in this circuit is insufficient to cause the operation of stepping relay 610. Switching relay 611 operates, however, and performs the following circuit changes: Ground potential is supplied to the test contact 855' and releases conductor 855 by way of wiper 662 and armature 648 and the working contact which is 100

connected to the release conductor 555. The trunk line is thus marked engaged and an obvious circuit is closed for the upper winding of switching relay 801 of connector RC which terminates the selected trunk line.

5 Switching relay 801 of connector RC operates in its first step to prepare the connector RC to receive the first set of impulses. In operating, relay 611 also prepares the circuit of reversing relay 602 at armature 649. At armature 650 a point in the initial circuit of stepping relay 610 is opened to prevent this relay from operating responsive to the dialing of the next digit. At armature 647 and 10 652 the connection is extended to the connector C, ground and battery through magnet 612 being disconnected from the heavy talking conductors, and ground and battery through rotary magnet 809 and relay 804 in series of connector RC being substituted therefor. Relay 608 remains energized over this circuit but relay 804 and magnet 809 do not operate due to the resistance in the circuit. At armature 651 a circuit is closed 15 which may be traced from ground by way of armature 628 and the resting contact, armature 651 and the working contact, wiper 663, bank contacts 857', ring-control conductor 857, armature 813 and the resting contact, 20 through the upper winding of ring-cut-off relay 802, resistance 850 to battery. Relay 802 operates, closes a locking circuit for itself at armature 818, closes a point in the busy signalling circuit at armature 819, and 25 at armatures 816 and 817 interrupts the ringing circuit, at the same time closing points in the talking circuit. A circuit is also closed from ground on the release conductor 855, off-normal springs 840 opened upon the first 30 vertical step of the switch wipers, through the lower winding of switching relay 807 to battery. Relay 807, which now functions as a change-over relay, operates and prepares a locking circuit for itself at armature 834, and 35 at armature 833 disconnects the rotary magnet 809 and connects the vertical magnet 808 in series with the series relay 804 to the lower talking conductor by way of armature 815 and the resting contact. The actuation of 40 the other armatures of relay 807 has no effect at this time.

Responsive to the dialing of the next digit, resistance 619 and the upper winding of relay 608 are short circuited by the deenergization 45 of relay 605 as previously described and vertical magnet 808 operates to raise the switch wipers 841—844 opposite the level of bank contacts corresponding to the digit dialed. Relay 804 energizes in series with magnet 808 50 and due to its slow-acting characteristic is maintained operated continuously during the transmission of the impulses. The actuation of armature 822 closes the circuit of slow-acting relay 805. Relay 805 operates and maintains the locking circuit of relay 807 at armature

826, this circuit including armature 834. The circuit over which this relay is initially energized is opened at vertical off-normal springs 840 upon the first vertical step of the switch wipers. At the end of this series of impulses relays 804 and 805 release as the short circuit is no longer placed around resistance 619 and the upper winding of relay 608, and the locking circuit of relay 807 is interrupted. Relay 807 deenergizes and, by releasing armature 833, reconnects the rotary magnet 809 in series with relay 804.

70 Responsive to the last series of impulses, rotary magnet 809 operates to rotate the switch wipers 841—844 into engagement with the set of bank contacts terminating the first trunk of the group of trunks extending to the private branch exchange X. During the transmission of this series of impulses relay 804 and 805 again operate, relay 805 at armature 824 and the working contact connecting test relay 806 to wiper 842.

75 The operation of the connector RC following the positioning of the switch wipers 841—844 upon the bank contacts terminating the first trunk of the group extending to the private branch exchange X depends on whether this trunk is busy or idle at this time. It will be assumed that the first trunk of the group is the one terminating in bank contacts 845—848, and that the last trunk of the group is the one terminating in bank contacts 845'—848'. If the first trunk is busy at this time, ground potential will be present on bank contact 846, and bank contact 848 connected to bank contact 846 by way of the jumper 849. It may be mentioned that the test contacts similar to contacts 846 and 848 for all the other trunks of the group except the last trunk are connected together by means of jumpers such as jumper 849. As soon as wiper 842 engages test contact 846 a circuit is closed from ground potential on contact 846, wiper 842, armature 824 and the working contact, resting contact and armature 832, through the winding of test relay 806 to battery. Relay 806 operates and opens a point in the ring-back tone circuit at armature 827, prepares a circuit for the stepping relay 803 at armature 829, and prepares the busy-tone circuit at armature 827'. At the termination 100 of this last train of impulses, relay 804 deenergizes and by releasing armature 822 prepares a holding circuit for the auxiliary series relay 805 and closes a circuit for the stepping relay 803 at armature 823 which circuit may be traced from ground on test contact 848, wiper 844, armature 829 and the working contact, armature 823 and the resting contact, interrupting springs 836, through the winding of the stepping relay 803 to battery. Relay 803 operates and closes a locking circuit for itself at armature 821 which extends from ground on the release conductor 855, rotary off-normal springs 839 closed upon the first 105

110

115

120

125

130

5 rotary step of the switch wipers, working contact and armature 821, interrupting contacts 836, through the winding of relay 803 to battery. At armature 820 the energizing circuit for the rotary magnet 809 and the holding circuit for relay 805 are closed. These circuits may be traced from ground and release conductor 855, rotary off-normal springs 839, armature 820 and the working contact, then 10 by way of resting contact and armature 822, through the winding of relay 805 to battery, and also by way of the normally closed springs controlled by armature 833 through the winding of rotary magnet 809 to battery. 15 Consequently, relay 804 remains energized and magnet 809 operates rotating the switch wipers into engagement with the next set of bank contacts and also opening the circuit of stepping relay 803 at interrupting springs 836. Relay 803 deenergizes, opening its own 20 holding circuit at armature 821, and opening the circuit for relay 805 and magnet 809 at armature 820. Magnet 809 releases and again closes interrupting springs 836.

25 If the trunk line accessible in this next set of bank contacts is also busy, ground potential will again be present on both bank contacts corresponding to contacts 846 and 848. Again relay 803 will energize and close a circuit for magnet 809, which results in the 30 movement of the switch wipers into engagement with another set of bank contacts. In this manner the switch wipers will be rotated step by step until an idle trunk is found or 35 until the wipers are moved into engagement with the bank contacts 845'-848' terminating the last trunk of the group of trunks extending to the desired private branch exchange.

40 Assuming that wipers 841-844 are rotated into engagement with the bank contacts terminating the last trunk of the group, all the other trunks having tested busy, regardless of whether this last trunk is busy or idle, no 45 circuit will be again closed for stepping relay 803, since bank contact 848' is not connected with bank contact 846'. Consequently, the wipers will be arrested in this position.

50 It may be assumed that the last trunk of the group of trunks extending to the called private branch exchange is found idle when the rotary connector RC rotates its wipers 841-844 into engagement with the bank contacts 845'-848' terminating this trunk. No 55 ground potential will be present on the bank contacts 846', consequently test relay 806 will deenergize immediately upon the engagement of wiper 842 and bank contact 846'. In this case when relay 805 releases its armatures, relay 801 energizes, and a circuit is 60 closed which may be traced from ground on release conductor 855, armature 828 and the resting contact, through the upper winding of the switching relay 807, resting contact 65 and armature 824, wiper 842, bank contact

846', through the winding of switching relay 861 of the line switch LS^s, individual to the selected trunk, interrupting contacts 869 through the winding of the rotary magnet 863 to battery. Relay 807 and 861 operate 70 in this circuit, but due to the comparatively high resistance of relay 861 the current in the circuit is insufficient to cause the operation of magnet 863. Due to the usual mechanical interlocking arrangement between relay 861 and 862, relay 861 is permitted to operate just sufficiently to disconnect the normal connections of ground and battery through relay 862 from the line conductors. Relay 807 75 in operating, performs the following circuit changes: Ground potential is supplied to bank contact 846' at armature 831 and the working contact and wiper 842 to mark this trunk line busy. At armature 834, a holding circuit is closed for relay 807 which may be 80 traced from ground on the release conductor 855, rotary off-normal springs 839, armature 834 and the working contact, through the lower winding of relay 807 to battery.

85 Switching relay 801 energizing in its second step, effects the following results: The ground and battery connections are disconnected from the talking conductors by the operation of armatures 811 and 815, thereby interrupting the circuit of the impulsing relay 608 in the toll transmission selector TTS. At armature 813, the ring-control conductor 857 is disconnected from the upper terminal of ring-cut-off relay 802 and connected to the 90 lower terminal of this winding.

95 Relay 608, in deenergizing, closes points in the talking circuit by permitting armatures 640 and 642 to engage their resting contacts. By the release of armatures 641, the circuit 100 of relay 670 and lamp L^e is opened and a circuit for reversing relay 602 is closed which may be traced from ground by way of armature 641 and the resting contact, working contact and armature 649, through the winding of relay 602 to battery. Relay 602 operates 105 and performs the following circuit changes:

110 At armature 625, ringing relay 601 is bridged across condenser 695 in series with the condenser 696. A point in the initial energizing circuit of relay 608 is opened at armature 624. Ground is disconnected from conductor 556 at armature 622. By the operation of armature 623 battery through the upper winding of relay 605 is disconnected from conductor 554 and is connected through resistance 617 and the lower left-hand winding of repeating coil R^e to conductor 556. At armature 626 ground is removed from the ring control conductor 667, this taking place 115 before relay 802 is deenergized, armature 813 being operated. At the same point ground is connected to conductor 554 through the lower winding of relay 605, resting contact and armature 629, resistance 618, and the upper left-hand winding of repeating coil R^e. 120 125 130

Thus, the direction of current flow over the incoming toll trunk is reversed. Polarized relay 502 now operates and closes the circuit of lamp L⁴. The lighting of lamp L⁴ indicates to the toll operator that connection has been extended to the desired line.

After being notified that the connection has been extended to the desired substation, and that the line is idle at this time, the toll operator when ready throws the key K' to the ringing position, thereby connecting alternating current across the trunk conductors. In response to this alternating current, ringing relay 601 operates and extends ground by way of grounded release conductor 555, working contact and armature 621, armature 630 and the resting contact, armature 651 and the working contact, wiper 663, bank contact 857', conductor 857, armature 813 and the working contact to the lower terminal of ring-cut-off relay 802. Relay 802 is thereby short circuited, releases its armatures, and completes the ringing circuit for operating the drop signal at the P. A. X. This circuit may be traced from interrupted ringing generator over conductor 890, lower winding of relay 802, resting contact and armature 817, armature 835 and the working contact, wiper 843, bank contact 847', conductor 882, contacts 883 of jack J⁸, through the winding of signal relay 880, contacts 884 of jack J⁸, conductor 881, bank contact 845', wiper 841, working contact and armature 830, to ground at armature 816 and the resting contact.

When the P. A. X. attendant inserts a plug in jack J⁸ to answer the call, a direct current bridge in the attendant's cord circuit (not shown) is placed across the line conductors 881—882, which causes the operation of ring-cut-off relay 802 in the usual way. By the operation of armatures 816 and 817, the ringing circuit is opened and a circuit for the battery feed relay 603 of selector TTS is closed, this circuit including the upper and lower talking conductors and the line conductors of the called substation in series and the right hand windings of repeating coil R⁶. Relay 603 operates and closes a circuit for relay 604. Relay 604 operates and disconnects battery and ground connections from the conductors 554 and 556 at armatures 628 and 629, thereby opening the circuit of polarized relay 502 in the toll operator's cord circuit CC. Polarized relay 502 therefore releases its armatures and interrupts the circuit of the lamp L⁴. The extinguishing of lamp L⁴ notifies the toll operator that the called P. A. X. attendant has answered the call. The toll operator then informs the attendant of the P. A. X. subscriber wanted and the attendant sets up a local connection over the P. A. X. apparatus and signals the wanted subscriber. When the subscriber answers the attendant will disconnect her telephone set from the connection in the usual manner and

the loop through the called subscriber's telephone set will now serve to maintain the battery feed relay of selector TTS operated.

The toll operator at the main toll board now notifies the distant toll operator that connection has been completed with the called subscriber. The distant toll operator then makes the final connection, after which the calling subscriber who initiated the toll call and the called subscriber may engage in conversation.

At the end of the conversation both the calling subscriber and the called subscriber will replace their receivers. When the subscriber at the P. A. X. substation replaces his receiver, the bridge across the line conductors 881 and 882 is opened, interrupting the circuit of the battery feed relay 603. Relay 603 deenergizes and opens the circuit of relay 604. Relay 604 deenergizes and again connects battery and ground to conductors 556 and 554 which again causes the operation of the polarized relay 504 of the toll operator's cord circuit CD. In operating, polarized relay 502 closes the circuit of lamp L⁴. The lighting of lamp L⁴ at this time notifies the toll operator that the subscriber at the P. A. X. substation has replaced his receiver. She thereupon removes the plug P' from the jack J and gives the disconnect signal to the distant toll operator by any convenient means such as by operating the key K to the signaling position, connecting alternating current across the conductors of the incoming trunk (not shown).

Removing the plug P' from the jack J opens the circuits of the line relay 605 in the toll transmission selector TTS by opening the bridge across the trunk conductors 501 and 502. Relay 605 deenergizes and restores its armatures to normal. The engagement of armature 631 with its resting contact places a shunt around the winding of the release relay 606, thereby causing it to deenergize, shortly after which its armatures are restored to normal. Relay 609 is momentarily energized during the time that armature 631 is back and relay 606 is actuated, but its operation at this time has no utility. As a result of the restoration of relay 606, ground potential is removed from release conductor 555 at armature 633. The removal of ground potential from the release conductor 555 causes the release of the selectors TS and TTS and also of the connector RC. The removal of ground potential from the release conductor 555 also opens the circuit of the switching relay 611 in the toll transmission selector TTS. This relay thereupon deenergizes and restores its armatures to normal. The restoration of armature 649 also opens the circuit of the reversing relay 603 which thereupon deenergizes and restores its armatures to normal. A further result of the restoration of relay 606 is the closure of the circuit for the release magnet 614 which may be traced

from ground by way of the resting contact and armature 634, off-normal springs 655 closed upon the first vertical step of the switch wipers, through the winding of release magnet 614 to battery. Release magnet 614 energizes and restores the switch wipers to normal in the usual manner. In connector RC a circuit is also closed for release magnet 810 which may be traced from ground by 10 way of the resting contact and armature 812, vertical off-normal springs 838 closed upon the first vertical step of the switch wipers, through the winding of the release magnet 810 to battery. Magnet 810 operates and 15 causes the restoration of the wipers 841—844 of the connector RC to normal. All the apparatus used in setting up the toll connection from the toll board to the P. A. X. has now been restored to normal and is ready to 20 be used in the establishment of another connection. The attendant releases the switches in the P. A. X. in the usual way by removing the plug from jack J⁸.

If the last trunk of the group had been 25 busy instead of idle as just described, test relay 806 would remain operated. Relay 805, which is maintained energized during the hunting movement of the switch by reason of the fact that a circuit is closed each 30 time armature 820 operates, being no longer energized, releases. In releasing its armature 824, a locking circuit is closed for test relay 806 from ground on release conductor 855, armature 828 and the working contact, 35 normally closed springs controlled by armature 824, resting contact and armature 832 through the winding of test relay 806 to battery. By the release of armature 826 a circuit is closed which may be traced from 40 ground on release conductor 855, rotary off-normal springs 839, armature 826 and the resting contact, off-normal springs 837 closed on the first vertical step of the switch wipers, through the lower winding of two-step relay 45 801 to battery. Relay 801 operates in its second step, disconnecting the normal connections of ground and battery through relay 804 and magnet 809 from the upper and lower talking conductors at armatures 811 and 815, 50 and opening the circuit of its initial energizing winding at armature 814. The disconnection of battery and ground from the talking conductors of the trunk causes relay 608 of the transmission selector to release and 55 switch over the connection to talking position as previously described and connect up battery feed relay 603. By the operation of armature 827, interrupted battery potential is extended by way of the common conductor 602, working contact and armature 819, armature 827 and the working contact, working contact and armature 815, conductor 856, bank contact 856', wiper 664, armature 652 and the working contact, armature 642 and 60 the resting contact, armature 638 and the

resting contact, lower right-hand winding of repeating coil R⁶, through the lower winding of battery feed relay 603 to battery. As a result, relay 603 energizes and deenergizes, alternately opening and closing the circuit of relay 604. Relay 604 operates its armatures 628 and 629 to intermittently open and close the circuit of the polarized relay 502 in the cord circuit CC. This causes the polarized relay 502 to intermittently open and close the circuit of the lamp L⁴ which causes the lamp to flash. The flashing of the lamp L⁴ notifies the operator that the called line is busy, whereupon she will remove the plug P' from the jack J to release the connection, as previously described. Conductor 692 may be connected to an interrupter such as interrupter I⁵ shown in Fig. 1. It is preferable that a different rate of interruptions be used in the two instances so that the operator will receive different signals for line busy and all trunk busy conditions.

In the above description it was assumed that the selectors in performing their rotary hunting movement always found an idle trunk over which to extend the connection to a succeeding switch. Under extreme traffic conditions, however, there is a possibility of all the trunks accessible in a selected level of bank contacts being busy at the particular time that the testing operation is performed. In such a case the particular selector rotates its wipers past the last set of bank contacts to the eleventh rotary step in which position of course the rotary motion automatically steps, since the test wiper engages no contact.

The toll first selectors are provided with rotary cam springs which operate when the wipers are moved to the eleventh positions and connect the ground and interrupted battery supply to the incoming trunk conductors producing an interrupted current flow over the conductors in such a direction as to intermittently operate the polarized relay in the cord circuit and cause the flashing of the supervisory lamp. For example should selector TS (Fig. 1) rotate its wipers to the eleventh rotary position, finding all trunks in the selected level busy, cam springs 511 and 512 are closed, thereby connecting ground and interrupted battery from interrupter I⁵ to trunk conductors 501 and 502, respectively. The resulting current flow through the polarized relay 502 of the cord circuit CC is such as to cause relay 502 to operate intermittently and close the circuit of lamp L⁴. The flashing of lamp L⁴ notifies the toll operator of the all trunks busy condition encountered.

In the toll transmission selectors a different method is employed for causing the flashing of the supervisory lamp in the toll operator's cord circuit. Should toll transmission selector TTS (Fig. 2) rotate its

wipers to the eleventh rotary position, finding all trunks in the selected level busy, cam springs 657 are closed, thereby connecting conductor 692 to the upper talking conductor. Conductor 692 is connected to interrupter I^5 (Fig. 1) or a similar interrupter. A circuit for relay 603 which includes the upper right hand winding of repeating coil R^6 is alternately closed and opened. In addition to this, the rotation of the switch wipers 661—664 off of the bank contacts removes the ground potential from the lower terminal of the winding of switching relay 611, thereby permitting this relay to energize. Since 10 wipers 661 and 664 are not now connected to ground and battery through the vertical magnet of the sounding switch as they ordinarily would be if an idle trunk had been found, the circuit of holding relay 608 is 15 opened and that relay deenergizes. Relay 608 in deenergizing closes a circuit from ground by way of armature 641 and the resting contact, working contact and armature 649 (relay 611 now being energized) through 20 the winding of relay 602 to battery. Relay 25 602 operates and reverses the ground and battery connections to the incoming trunk conductors thereby reversing the direction of current flow through the winding of polarized relay 502 in the operator's cord 30 circuit CC which causes the relay to operate. The intermittent connection of battery to the upper talking conductor by way of cam 35 springs 657 causes relay 604 to energize and deenergize. Relay 604 energizes and deenergizes correspondingly and at armature 628 and contacts controlled thereby intermittently disconnects battery from conductor 556. These interruptions cause polarized 40 relay 502 to energize and deenergize and lamp L^4 flashes to indicate that an all trunks busy 45 condition has been encountered. The operator will of course release a connection under these conditions, the release being in the manner previously described.

The utility of alarm relay 690 (Fig. 2) will now be described. When toll transmission selector TTS is taken into use relay 608 operates and closes a circuit for lamp L^6 and relay 690 from ground, armature 641 and the working contact and armature 643 and the resting contact. Lamp L^6 lights and relay 690 operates. Relay 690 closes a circuit lamp L^6 and also connects ground to a signal conductor leading to the usual slow operating alarm circuit (not shown). Relay 609 operates in response to each series of digits dialed and interrupts the above circuit for relay 690 at armature 643. When the called line is 55 connected with or an all trunks busy condition is encountered, relay 608 releases and also opens the circuit of relay 690. The slow alarm circuit is adjusted so that it does not operate a signal until ground has been maintained on the alarm conductor for a longer

time than is ordinarily allowed between successive digits. Should the operator fail to dial after seizing selector TTS or fail to dial the complete number, the alarm circuit will function to notify the exchange attendant of the fact. The attendant is enabled to locate the fault quickly by means of the signal lamps, lamp L^6 being individual to a selector TTS and lamp L^6 being common to a group of such selectors.

Having described the invention, what is thought new and is desired to have protected by Letters Patent will be pointed out in the appended claims.

What is claimed is:

1. In a telephone system, operator controlled means for setting up a connection to a called line, a relay controlled by the answering of the called party for giving the operator a signal, operator controlled means for disconnecting said relay and for ringing on the called line while the same is in answered condition, and means for maintaining said relay operated during the ringing operation.

2. In a toll transmission selector, a relay bridged across the talking conductors thereof, a magnet bridged across said talking conductors in series with a source of current, and means responsive to impulses for intermittently short circuiting said relay to cause said magnet to operate said switch.

3. In a telephone system, a rotary connector switch having a vertical directive movement, a rotary directive movement, and a rotary hunting movement, a trunk line terminating in said switch, a vertical magnet and a rotary magnet, means for successively bridging said magnets across the talking conductors of said trunk line, means for sending impulses corresponding to the last two digits of a called number over the two talking conductors of said trunk line in series for causing said magnets to successively operate said switch in its vertical directive and rotary directive movements, and means responsive to the completion of the rotary directive movement for disconnecting said rotary magnet from in bridge of said talking conductors and for closing a local stepping circuit for said rotary magnet to initiate the rotary hunting movement of the switch.

4. In a telephone system, two automatic switches, means for successively operating said switches to extend a connection, a double wound relay in said first switch, a stepping magnet in the second switch, means for continuously energizing said relay over a local circuit including one of its windings during the operation of the first switch, means for energizing said relay over a circuit including its other winding and said magnet in series at the completion of the operation of the first switch, means in the second switch for opening the latter circuit at the

completion of the operation of the second switch, and a second relay operated responsive to the release of said first relay.

5. In a toll service trunking system, a toll transmission selector and a toll connector arranged to be operated in tandem to set up a connection, stepping magnets in said selector and said connector bridge across the talking circuit in series with a source of current, a control relay in said selector held up in series with one or the other of said magnets while the connection is being set up, means for cutting off the magnet at the connector to deenergize said control relay, and a battery feed bridge at said selector connected up responsive to the deenergization of said relay.

6. In a toll service trunking system, a toll transmission selector and a toll connector, stepping magnets in said selector and said connector, a control relay in said selector held up in series with one or the other of said magnets while a connection is being set up, means for cutting off the magnet at the connector to deenergize said control relay, a trunk line extending from a switchboard to said selector, and means responsive to the deenergization of said control relay for reversing the current over said trunk line.

7. In a telephone system, two automatic switches, a trunk line extending from a switchboard to the first switch, means for successively operating said switches to extend a connection, a double wound relay in the first switch, means for continuously energizing said relay over a local circuit including one of its windings during the operation of the first switch, means for energizing said relay over its other winding over a circuit extending to the second switch at the completion of the operation of the first switch, means in the second switch for opening the latter circuit at the completion of the operation of the second switch to deenergize said relay, and means responsive to the deenergization of said relay for reversing the direction of current flow over said trunk line.

8. In a telephone system, two automatic switches, an operator's position, means for successively operating said switches to extend a connection from said position, a double wound relay in the first switch, means for continuously energizing said relay over a local circuit including one of its windings during the operation of the first switch, means for energizing said relay over its other winding over a circuit extending to the second switch at the completion of the operation of the first switch, means in the second switch for opening the latter circuit at the completion of the operation of the second switch to deenergize said relay, and a signal at said position operated responsive to the deenergization of said relay.

9. In a telephone system, two automatic switches, a trunk line terminating in the first

switch, a relay in the first switch bridged across the talking conductors of said trunk line in series with a source of current, means controlled over said trunk line for successively operating said switches to extend a call, a control relay in the first switch energized over a local circuit during the operation of the first switch and over a circuit extending to the second switch at the completion of the operation of the first switch, means in the second switch for opening the latter circuit at the completion of the operation of the second switch to deenergize said control relay, and means responsive to the deenergization of said control relay for reversing the conductors of said trunk line with respect to said first relay and said source of current.

10. In a telephone system, two automatic switches, a trunk line terminating in said first switch, means for establishing a normal current flow over the talking conductors of said trunk line, means for successively operating said switches to extend a call, a control relay in the first switch energized over a local circuit during the operation of the first switch and over a circuit extending to the second switch at the completion of the operation of the first switch, means in the second switch for opening the latter circuit at the completion of the operation of the second switch to deenergize said control relay, means responsive to the deenergization of said control relay for reversing the direction of current flow over the trunk line, and means responsive to the answering of the call for stopping the current flow over the trunk line.

11. In a toll service trunking system, a toll transmission selector and a toll connector connected by a trunk line, a motor magnet in said connector bridged across the talking conductor of said trunk line, and means in said selector for controlling the operation of said magnet over the two conductors of said trunk line in series to position and connector.

12. In a toll service trunking system, a toll transmission selector and a toll connector connected by a trunk line, a motor magnet in said connector for controlling the positioning of the connector, a closed circuit for said magnet including a source of current and the two talking conductors of said trunk line in series, and means in said selector for altering the current flow in said circuit to control the operation of said magnet.

13. In a toll service trunking system, a toll transmission selector and a toll connector connected by a trunk line, a motor magnet in said connector for controlling the positioning of the connector, and means in said selector for sending impulses directly to said magnet over the two talking conductors of said trunk line in series.

14. In a toll service trunking system, means

for establishing a talking connection including a toll transmission selector and a toll connector, and means in said selector for repeating digits of a called number directly to the magnets of said connector over a circuit including the two talking conductors in series.

15. In a toll service trunking system, a train of serially related automatic switches including a transmission selector and a toll connector, a stepping magnet in each switch, a trunk line connecting the switches, and a line relay in the selector for operating said magnets, the magnet of the connector being operated over the two talking conductors of the trunk in series.

15. In witness whereof, I hereunto subscribe my name this 12th day of July, A. D. 1929.

JOHN WICKS.
